UNITED STATES PATENT OFFICE.

JAMES J. WOOD, OF FORT WAYNE, INDIANA.

SINGLE-PHASE MOTOR.

No. 878,923.

Specification of Letters Patent.

Patented Feb. 11, 1908.

Application filed April 26, 1906. Serial No. 313,790.

To all whom it may concern:

Be it known that I, JAMES J. WOOD, a citizen of the United States, residing in Fort Wayne, in the county of Allen and State of Indiana, have invented certain new and useful Improvements in Single-Phase Motors, of which the following is a specification.

This invention relates to a single-phase motor which starts as a commutator motor and operates as an induction motor. The motor is inverted, the rotor being the primary and the stator the secondary. The single-phase current is fed to the rotor coils through a commutator at starting, and through collectors 10 and 15 during normal running. The secondary or stator has its winding short-circuited upon itself in a definite line, so as to develop fixed magnetic poles for starting, and its coils are short-circuited along preferably a plurality of lines for normal running.

In the preferred embodiment of my invention herewith illustrated, the motor is adapted to start as an inverted repulsion motor. Accordingly, to attain a high initial starting torque, the axis of the commutator brushes is displaced from the magnetic axis of the secondary or stator to a sufficient angle to give the required torque.

The motor is adapted preferably to be started by manual control; for this purpose a starting handle or lever is provided which is displaced to one position for starting, and, when a sufficient speed has been attained, is thrown to another position for normal running. This handle is connected through suitable intermediaries to the respective brush-holders, so that, in moving it to the starting position, the commutator brushes are applied and the collector brushes are lifted; and in moving it thence to the running position the commutator brushes are lifted and the collector brushes are applied. In the intermediate or stopped position preferably both sets of brushes are lifted.

Figure 1 of the accompanying drawings is mainly a vertical midsection in the plane of the rotor shaft axis of a motor constructed according to the preferred embodiment of this invention. Fig. 2 is a transverse section mainly on the line 2--2 in Fig. 1, viewed from the right, the right-hand end plate and bearing being removed. The portion of Fig. 2 broken away at the right is in section on the line x--x in Fig. 1. Fig. 3 is a circuit diagram of a two-pole machine, the stator secondary being shown as delta-connected. Figs.

4, 5 and 6 are vertical longitudinal sections showing the brush-operating parts in the stopped, starting and running positions respectively. Figs. 7, 8 and 9 are fragmentary transverse sectional elevations, showing the position of the brush-holders in the starting, stopped and running positions respectively. Fig. 10 is a diagram of the rotor and brush circuit connections. Fig. 11 is a diagram showing the stator winding Y-connected. Fig. 12 is a diagram illustrating the conditions of the stator for a four-pole machine. Fig. 13 is a winding diagram for a four-pole stator.

Let A designate the rotor with its primary winding P.

Let B designate the stator with its secondary winding S.

The rotor and stator have laminated cores formed preferably with slots for the windings or coils in the usual manner (in Fig. 2 the coils are omitted, and a few of the slots are shown).

The motor may have any suitable number of poles; it is shown in Figs. 1 and 2 as a four-pole machine, but to simplify the circuit diagrams, Figs. 3, 10 and 11, it is there shown as a two-pole machine.

The rotor shaft C carries a commutator D and collectors or rings E E. The shaft turns as usual in bearings formed in heads F F attached to the opposite ends of a main frame or casing G, or according to any other usual or suitable mechanical construction.

The rotor may be wound according to any system adapted to the primary of an induction motor and adapted also as the rotor of a commutator motor. Thus it may be arranged like the armature winding of a direct-current motor. For a two-pole machine it may be wound with a simple gramme winding G, as shown in Fig. 3, its coils having direct connection with the commutator segments; for a multipolar machine this winding will be suitably modified, for example according to the methods well understood in winding the armatures of direct-current multipolar machines. The rotor winding is connected at suitable points with the collector rings E E, this connection for a two-pole machine being made with diametrically opposite commutator segments, as shown in Fig. 3, and being modified in the well understood manner for a multipolar winding.

The stator is wound as a three-phase armature, or according to any system of winding

suitable for the armature or secondary of an induction motor, and adapted when partly open-circuited to develop the required number of fixed magnetic poles with which the 5 rotor may react as an inverted repulsion motor in starting. To this end the stator winding is short-circuited upon itself upon a definite line at a suitable angle to the line of contact of the commutator brushes. For normal 10 running it is further short-circuited on a second line at an angle to the first, and is preferably symmetrically short-circuited on a plurality of lines, after the manner of the armature of an induction motor. This short 15 circuit may be opened or closed by any suitable switch, such as the switch H, which is shown as a knife-switch having fixed blades a a engaged by movable blades b.

The commutator brushes J J for starting 20 are carried by brush-holders K K of any suitable kind, each of these being mounted on a movable carrier L. The collector brushes M M are carried by brush-holders N N of any suitable construction, which latter holders 25 also are mounted upon or otherwise suitably connected to the respective carriers L L. The particular construction of the brush-holders K N, and the means for insulating them from each other and preferably from 30 the carriers, form no necessary part of the present invention and need not be described.

For starting the motor, a starting handle R is provided, constructed preferably as a lever engaging an oscillatory shaft Q. Whatever 35 be the mechanical construction, the starting handle R should be movable to three positions and be so connected to the respective commutator and collector brushes and to the switch H that in the starting position of the handle the commutator brushes K are caused to bear upon the commutator, the collector brushes M are lifted from their respective rings, and the switch H is open; in the running position of the handle the 40 commutator brushes are lifted, the collector brushes are applied to their rings, and the switch is closed; and in the third (preferably intermediate) position of the handle both the commutator and collector brushes are lifted, 45 and the switch is preferably open. The operating handle may be variously connected to the brushes and switch for communicating to them the requisite movements when the handle is shifted from one position to another.

In the preferred construction shown, 55 where the handle is a lever fixed to a shaft Q, the brushes are operated by cams on this shaft, and the switch is operated by its movable member being directly connected to the 60 shaft. The shaft Q extends transversely to the motor under the commutator; at preferably its middle it has fixed to it a collar T to which is directly attached, through an insulation, the movable member or blades b of 65 the switch. At suitable points cams U U are

fixed on the shaft for operating the brush-carriers L L. These cams are shown as simple collars with a flat face which, in the starting position, Fig. 4, is level, and in the running position, Fig. 6, is up-tilted. These 70 cams engage plungers V V which are directly connected to the respective brush-carriers L L, shown best in Fig. 2. Each plunger is pressed downward by a spring e and is adjustable in length, its upper portion consisting 75 of a rod or link d the lower end of which is threaded and screws into the lower part of the plunger, the latter being made nonrotative, as by forming it exteriorly as a polygon and arranging it to move freely in a closely-fitting polygonal socket which is conveniently formed in an inward projection e from the main frame G, as best shown in Fig. 2.

To start the motor, the handle R is pressed manually over to the starting position, 85 where it is held (preferably against the stress of a spring which seeks to throw it back) until the motor is brought up to speed or approximately so. While thus held the brushes J are applied to the commutator and 90 the brushes M are lifted from the collector rings, as shown in Figs. 2 and 7, and the switch H is open, as shown in Figs. 1, 3 and 4. Then the operator quickly throws the starting lever to the opposite extreme position, as indicated in Fig. 6, thereby lifting the commutator brushes and applying the collector brushes, as shown in Fig. 9, and closing the switch, as shown in Fig. 6. The stator or secondary coils are thus short-circuited at three points, as in any three-phase winding, the single-phase alternating currents being conducted through the collector rings to the coils of the rotor, so that the motor operates as an inverted induction 105 motor. To stop the motor, the controlling handle is moved to the intermediate or stopping position, thereby lifting both sets of brushes, as in Fig. 8.

It is important to provide means for resisting the displacement of the operating handle to the starting position, which is adapted, if the handle be prematurely released, to return it to the stopping position and thereby stop the motor rather than permit it to run indefinitely as a repulsion motor. It is desirable that this same means shall be utilized to hold the handle normally in the stopping position. For this purpose the shaft Q is provided with a cam W which 110 coacts with a spring Y. This spring is preferably a leaf spring and carries a roller f, which, in the stopped position, rests, as shown in Fig. 5, in a hollow g of the cam W. This cam (which is conveniently made integrally with the collar T) has on one side of the hollow g a toe h, which, as the operating handle is thrown to the starting position, bears downwardly upon the roller f, and flexes the spring, as shown in Fig. 4, so that by the 125 130

reaction of the spring against this toe a constant stress is afforded tending to restore the operating handle. In the stopped position the spring, by pressing the roller into the hollow g , resists any effort to turn the shaft in either direction, and so holds the operating lever in the stopped position. The cam W has on the opposite side of the hollow g a projection i having an approximately concentric exterior face, which, as the operating lever is turned to the running position, first expels the roller f from the hollow and then presents this concentric face against the roller, as shown in Fig. 6, where, by reason of the substantially concentric shape of the face, the spring pressure has no effect to turn the shaft in either direction, and consequently it remains in the running position shown, by reason of the frictional engagement of the roller with the cam, the frictional engagement of the leaves of the switch, and the engagement of the outer concentric portion of the cams U with the plungers V , which, in this position, (see Fig. 6) have no effect to turn the shaft. Consequently the controlling lever will remain in the running position until it is pushed back toward the stopped position sufficiently for the roller to run off the concentric face of i and reenter the hollow g .

It will be understood that the commutator brushes $J J$ are displaced around the commutator, with reference to the stator field axis, to the angle suitable for repulsion motor action, which commonly is in the neighborhood of twenty degrees. This is shown in Fig. 3 by the line $j-j$ which diverges from the stator field axis $y-y$, the latter being established by the short-circuiting of the stator winding between the points v and w , or, with the star connection shown in Fig. 11, from the point v' around clockwise to w' and thence to x' (the remaining winding from x' clockwise to v' being open-circuited). In Fig. 3 the external circuit wires $k k'$ leading to the brushes are shown by dotted lines, to distinguish them from the motor windings; and for greater clearness the commutator brushes $J J$ are shown within the segments instead of exteriorly. The exterior circuits are more clearly shown in Fig. 10, which indicates in an elementary manner the rotor circuit connections.

The stator may be wound according to any system which, when the winding is partially open-circuited, will develop the required number of poles corresponding with the winding of the rotor but in the preferred embodiment of my invention it is provided with a three-phase Y -connected winding. In a four-pole machine the winding may be such that at a given phase the currents induced in the stator winding will flow as indicated by the radial arrows in Fig. 12, thereby generating poles along the axes

$y-y$; the radial lines adjacent to the polar axes representing the portions of the winding which are open-circuited in order to develop the poles for repulsion-motor starting. This result may be attained by means of a three-coil winding, each coil being distributed according to the number of poles, so that between each pole and the next the winding is equally divided between the three coils. An example of a suitable winding for a four-pole machine is given in Fig. 13, which is a conventional winding diagram, the radial lines indicating the active portions of the winding lying in the stator slots, the inner connections being those at one end, and the outer connections those at the other end of the stator. The three coils are here indicated by a coarse line, a fine line, and a dotted line, respectively; and are Y -connected. The radii $y-y$ represent the axes of the magnetic poles of the stator when open-circuited for starting, and the radii $j-j$ indicate the positions of the commutator brushes.

My invention is susceptible of considerable modification in its electrical windings and connections, the number of magnetic poles, and in mechanical details, as will be readily apparent to those skilled in the art.

What I claim is:

1. In a single-phase motor, a rotor winding provided with both commutator and collector rings, connections for supplying current from an external source to said commutator and collector rings alternatively, and a stator winding short-circuited upon itself on a definite line.

2. In a single-phase motor, a rotor winding provided with both commutator and collector rings, connections for supplying current from an external source to said commutator and collector rings alternatively, a stator winding short-circuited upon itself on a definite line, and a switch in circuit with said stator winding arranged to short-circuit said winding on a second line at an angle to the first.

3. In a single-phase motor, a rotor winding provided with both commutator and collector rings, a set of commutator brushes, a set of collector brushes, connections for supplying current to said brushes from an external source, controlling means adapted to bring said brushes alternatively into operation, and a stator winding short-circuited upon itself on a definite line.

4. In a single-phase motor, a rotor winding provided with both commutator and collector rings, a set of commutator brushes, a set of collector brushes, connections for supplying current to said brushes from an external source, controlling means adapted to bring said brushes alternatively into operation, a stator winding short-circuited upon itself on a definite line, and a switch in circuit with said stator winding arranged to short-

circuit said winding on a second line at an angle to the first.

5. In a single-phase motor, a rotor winding provided with both commutator and collector rings, two sets of brushes adapted to engage said commutator and collector rings respectively, connections from both sets of brushes to an external source of current, means mechanically connected to said brushes for bringing them alternatively into engagement with said commutator and collector rings respectively, and a stator winding short-circuited on itself on a definite line.

6. In a single-phase motor, a rotor winding provided with both commutator and collector rings, two sets of brushes adapted to engage said commutator and collector rings respectively, connections from both sets of brushes to an external source of current, means mechanically connected to said brushes for bringing them alternatively into engagement with said commutator and collector rings respectively, a stator winding short-circuited on itself on a definite line, and a switch in circuit with said stator winding arranged to short-circuit it on a second line at an angle to the first.

7. A single-phase motor comprising a rotor primary, a stator secondary short-circuited on a definite line, a commutator and collector rings connected to the rotor winding, and means for introducing current from an external source to the rotor through the commutator for starting and through the collector rings for normal running.

8. A single-phase motor comprising a rotor primary, a stator secondary short-circuited on a definite line, a commutator and collectors for the rotor, commutator and collector brushes, means for lifting the commutator brushes and applying the collector brushes, or vice versa, and connections for supplying current to said brushes from an alternating current source.

9. A single-phase motor comprising a rotor primary, a stator secondary short-circuited on a definite line, a commutator and collectors for the rotor, commutator and collector brushes, an operating handle, means connecting said handle and brushes adapted in the starting position of the handle to apply the commutator brushes and lift the collector brushes, and in the running position of the handle to lift the commutator brushes and apply the collector brushes, and connections for supplying current to said brushes from an alternating current source.

10. A single-phase motor comprising a rotor primary, a stator secondary short-circuited on a definite line, a switch for short-circuiting the stator on a second line at an angle to the first, a commutator and collectors for the rotor, commutator and collector brushes, an operating handle, means connecting said handle with the respective

brushes and with said switch adapted in the starting position of the handle to apply the commutator brushes and lift the collector brushes and open the switch, and in the running position of the handle to lift the commutator brushes and apply the collector brushes and close the switch, and connections for supplying current to said brushes from an alternating current source.

11. A single-phase motor comprising a stator secondary, a rotor primary having a commutator and collector rings, commutator and collector brushes, an operating handle, means connecting said handle to said brushes adapted to lift either set while applying the other, and means for pressing said handle from the starting to the stopped position.

12. A single-phase motor comprising a stator secondary, a rotor primary having a commutator and collector rings, commutator and collector brushes, an operating handle, means connecting said handle to said brushes adapted to lift either set while applying the other, and yielding means for holding said handle in the stopped position and resisting its displacement to the starting position.

13. A single-phase motor comprising a stator secondary, a rotor primary having a commutator and collector rings, commutator and collector brushes, an operating handle, means connecting said handle to said brushes adapted to lift either set while applying the other, and yielding means for holding said handle in the stopped position and resisting its displacement toward either the starting or running positions.

14. A single-phase motor comprising a stator secondary, a rotor primary having a commutator and collector rings, commutator and collector brushes, an operating lever, an oscillating cam-shaft connected thereto, and connections therefrom to the respective brushes adapted as the shaft is oscillated to lift either set of brushes and apply the other.

15. A single-phase motor comprising a stator secondary, a rotor primary having a commutator and collector rings, commutator and collector brushes, rocking carriers each supporting one commutator and one collector brush, an operating handle, and means connecting said handle to said carriers adapted in an intermediate position of the handle to lift all the brushes, in a starting position of the handle to rock said carriers to apply the commutator brushes, and in a running position of the handle to oppositely rock said carriers to lift the commutator brushes and apply the collector brushes.

16. A single-phase motor comprising a stator secondary, a rotor primary having a commutator and collector rings, commutator and collector brushes, an operating le-

- ver, connections therefrom to the respective brushes adapted to lift either set while applying the other, a cam in connection with said lever, and a spring engaging said cam, reciprocally adapted to apply the stress of the spring to restore the lever from the starting to the stopped position and resist its displacement from the latter toward either the starting or running position.
10. 17. A single-phase motor comprising a rotor having a commutator and collector rings, commutator and collector brushes, an operating lever, an oscillating shaft connected thereto, and connections therefrom for operating the respective brushes, a spring-pressed roller, a cam fixed on said shaft and coöperating with said roller, having a hollow entered thereby in the stopped position of the lever, a toe adapted to press back the roller in the starting position, and a projection adapted to expel the roller in moving to the running position and having an approximately concentric outer face receiving the roller in the running position.
15. 18. An alternating-current motor having a rotor winding provided with both commutator and collector rings, two sets of brushes adapted to engage said commutator and collector rings respectively, an operating handle and connections therefrom for shifting the brushes adapted in one position of the handle to lift the collector brushes and apply the commutator brushes, and in another position to lift the commutator brushes 30 and apply the collector brushes, and connections from the brushes to an alternating current source.
20. 19. A single-phase motor comprising a rotor provided with a winding connected to a
- commutator and to collector rings, a polyphase stator winding having a portion only of its phases short-circuited at starting, connections for supplying current from an alternating-current source to the rotor winding through the commutator at starting and 45 through the collector rings for running, and means for short-circuiting all the phases of the stator winding when the motor is up to speed.
20. 20. A single-phase motor comprising a rotor provided with a winding connected to a commutator and to collector rings, a stator provided with a three-phase winding having two of its terminals connected together, connections for supplying current from an 50 alternating current source to the rotor winding through the commutator at starting and through the collector rings for running, and means for completely short-circuiting the 55 stator winding for running.
21. 21. A single-phase motor comprising a rotor provided with a winding connected to a commutator and to collector rings, a stator provided with a Y-connected three-phase winding having two of its terminals connected together, brushes for supplying current from an alternating-current source to said commutator at starting and to said collector rings for running, and a switch for connecting the third terminal of the stator 60 winding to the other two for running.

In witness whereof, I have hereunto signed my name in the presence of two subscribing witnesses.

JAMES J. WOOD.
